UNITED STATES PATENT OFFICE.

HARRY GUY BARTHOLOMEW AND MAYNARD L. D. McFARLANE, OF LONDON, ENGLAND.

TELAUTOGRAPHY OR PHOTOTELEGRAPHY.

Application filed October 12, 1923, Serial No. 668,243, and in Great Britain October 16, 1922.

This invention relates to telautography or phototelegraphy.

In the specifications of our applications for British Letters Patent No. 195,577 and 5 No. 197,402, we have described certain methods of telautography involving inter alia the production of an intermediate record of the original in the form of a punched tape of the character employed in the five 10 unit code, that is to say, a punched tape in which each unit consists of a group of holes arranged transversely to the direction of travel of the tape, and in the specifications in question there is described the employment 15 of a tape of this character in controlling directly the exposure of successive small areas of a light sensitive surface in order to produce thereon a visual representation of the original.

20 The main object of the present invention is to provide an apparatus having an optical system enabling the exposure to be conveniently controlled in this manner.

The invention consists broadly in an apparatus 25 in which the perforated tape operates directly to permit or interrupt the passage of light to the light sensitive surface from a suitable source comprising an optical system adapted to secure the projection 30 on to the light sensitive surface of an image or spot of light the form of which shall be substantially independent of the number of individual holes constituting a group through which the light forming the 35 image is simultaneously passing.

The invention consists in various novel features, constructions and combinations of parts as will hereinafter appear and be specifically pointed out in the appended 40 claims.

By these means the light passing through the several holes of a group which if a projection lens of the usual form without modification were used would form a plurality of spots or light side by side on the light sensitive surface, or at best a band of light, is concentrated or caused to converge by the first lens to a straight line in one plane while the second lens causes the 45 lateral converging of said line to a point, with the result that a spot of light which is of a width substantially equal to its height may be projected independently of the number of holes constituting the group through 50 which light is passing.

Satisfactory gradation cannot be secured

by the employment of tones produced by exposing a light sensitive surface to light, the intensity of which varies directly and in simple relationship with the number of 60 the dots; that is to say, the desired gradation cannot be secured if the maximum depth of tone is represented by the light transmitted through five holes, the next lighter tone by the light passing through four 65 holes and so on, as the gradation should be steeper than that which can be secured in this manner.

The invention also extends to the provision of means for securing the desired steepness of gradation. 70

Such means may comprise any suitable device for securing the passage, through the several marking holes constituting a group, of light the intensity of which varies in accordance with the position of the marking hole. 75

Thus, for example, in the gate, apertures may be arranged in a plate 37 at the gate 80 36 positioned to register with a plurality of holes in a group, such apertures being wider at one end 10 than at the other 10, the narrower end being adjacent that over which the hole representing the lightest tint will pass. It is found that with a tape of the 85 character indicated in which the tones are represented by one, two, three, four or five dots arranged transversely to the direction of travel of the tape, the apertures are conveniently bounded on their longest sides 90 by a straight line, while the opposite side is bounded by a parabolic curve; it is, however, to be remarked that the invention is not limited to devices provided with apertures of this form. 95

As will be understood by those acquainted with the perforating and reperforating machines used in telegraphy, feed holes are formed in the tape and with a tape in which the maximum number of marking holes representing the maximum depth of tone is five these feed holes come between the second and third of the holes of a group. 100

It is not desirable that the light should be permitted to pass through these feed holes 105 as the tonality of the reproduction would thus be degraded.

The invention includes the provision of means whereby these holes are obscured.

In the preceding paragraphs apertures in 110 the gate have been referred to, the plural being used to include the singular, as while a

division may be arranged to obscure the marking holes, this division could be omitted and a single aperture be provided with which the whole of the individual members of each group of holes would register.

In the apparatus according to the invention the tape may be caused to travel continuously or intermittently through the gate past the aperture or apertures therein, the light sensitive surface being moved similarly in a continuous or intermittent manner. It is found preferable to move both the tape and the light sensitive surface continuously and to arrange the light sensitive surface upon a cylindrical mandrel to which is imparted a rotatory and translatory motion so that the light projected upon the light sensitive surface is caused to travel over the same in a helical path.

20 One construction in accordance with the invention is illustrated by way of example in the accompanying drawings:—

Figure 1 being a longitudinal section in a vertical plane of the essential portion of the projector and the device adapted to contain the light sensitive surface.

Figure 2 is a corresponding sectional plan view;

Figure 3 a view of a detail, and

30 Figure 4 a front view of the projector with the face plate and lenses removed to expose the apertures in the gate.

The apparatus comprises a fixed source of light of substantially constant intensity acting as illuminating means for the holes in common.

40 A casing 2 is arranged to contain the spools 3, 3^a journaled on shafts 5, 5^a, guiding the perforated tape 35 through a gate 36. The gate comprises a front member 8, a rear member 7, and a gate plate 9. Rays from a source of light such as an electric arc lamp pass through an aperture 38 in the wall 1 of the chamber containing said arc lamp and strongly illuminate the tape passing through the gate 36. On the front wall of the casing co-axially with the gate 36 is carried the lens mounting 14 comprising an inner stationary member 15 and draw tube 16. Arranged on 50 a stationary tube carried on the base of said mounting are arranged the two plano cylindrical lenses 33, 34 with their longitudinal axes at right angles to one another. On the draw tube 16, fitted with a handling cap 20, is mounted a microscope objective 17.

55 The sensitized film 29 on which the light passing through the punched tape is to fall is arranged within a light tight casing 32, on a mandrel 30 mounted on a shaft 31. An aperture 28 is provided for the passage of the pencil of light passing through the microscope objective 17 and this aperture may be closed by a slide 23.

60 The pair of lenses 33, 34 of cylindrical form are employed one arranged behind the

other, the one 33 adjacent to the tape having its axis parallel with the axes of the groups of holes while the other 34 is arranged with its axis at right angles to the axis of the first-mentioned lens.

70 As will be understood, the cylindrical lenses are merely longitudinal sections of cylinders having one convex cylindrical.

The punched tape 35 is caused to travel through a gate 36 adapted to permit light to pass simultaneously through a single group of holes only, the optical system comprising the cylindrical lenses being arranged between the gate and the light sensitive surface.

75 Alternatively, an astigmatic optical system 80 or lens of any suitable form adapted to secure the projection on to the light sensitive surface of an image, the form of which shall be substantially independent of the number of individual holes constituting a group 85 through which the light forming the image is simultaneously passing, may be employed.

80 For example, any optical system (of which many forms are known) may be employed in which the source of light (rather than the openings) is imaged on the film. In this case the apertures are utilized to regulate the amount of light passed onto the film and not as an object to be imaged.

85 In the specific lens system herein illustrated, as well as in other systems, which would accomplish the same purpose, the tape and film must be properly located with respect to the lenses and the curvature of said lenses, so that the above-mentioned desired effect can 100 be secured.

90 Having now described our invention, what we claim as new and desire to secure by Letters Patent is:—

1. Apparatus for use in telephotography 105 adapted automatically to produce a reproduction of a transmitted original, comprising a source of light, means for supporting a light sensitive surface, optical means for projecting light from said source upon said surface, means to support an intermediate record of said original in the form of a non-pictorial record in position to control light passing from said light source to said light sensitive surface, means adapted to concentrate said light passing to said sensitive surface to form a single spot upon said surface, and means to move said light sensitive surface and intermediate record, so that consecutive points on said record control the 110 light falling on consecutive points of said surface.

115 2. Apparatus for use in telephotography adapted automatically to produce a reproduction of a transmitted original comprising 120 a source of light, means for supporting a light sensitive surface, optical means for projecting an image of the source of light upon said light sensitive surface, means to support an intermediate record of said origi- 125 130

nal in the form of a non-pictorial representation positioned to control light passing from said light source to said light sensitive surface, and means to move the light sensitive surface and intermediate record so that consecutive points on said record control the light falling on consecutive points of said light sensitive surface.

3. Apparatus as claimed in claim 1, in which the non-pictorial representation is arranged in the path of light passing from the light source to a light sensitive surface, the amount of light falling upon the light sensitive surface being directly controlled by the light transmitting characteristic of successive portions of said record.

4. Apparatus as claimed in claim 1, in which the means for maintaining and guiding said intermediate record comprise a gate 20 provided with an elongated aperture wider at one end than the other, the narrower end being at that side of the gate over which the portion of the intermediate record representing the lightest tint of the original is moved.

5. Apparatus as claimed in claim 1, in which the means for moving said light sensitive surface comprise a mandrel and means for simultaneously rotating and causing longitudinal movement of said mandrel.

6. Apparatus as claimed in claim 2, in which said optical means comprise two plano cylindrical lenses arranged on the longitudinal axis of the path of the light, with their plane surfaces toward the series of light and at right angles to each other.

7. In combination a source of light, a perforated tape or the like having a plurality of series of perforations, the combined

area of each said series corresponding to the tone value of a small area of a picture to be reproduced, means adapted to support and move said tape in front of said source of light so that the light can pass through said perforations, means adapted to concentrate the light rays passing through said perforations to a single spot of light, and means adapted to project said spot of light on a light sensitive surface.

8. Apparatus for use in telephotography adapted to produce a reproduction of a transmitted original comprising a source of light, means for supporting a light sensitive surface, optical means for projecting light from said source upon said surface and means to control the light passing from said light source to said light sensitive surface and optical means to concentrate said light passing to said sensitive surface to form a single spot upon said surface.

9. Apparatus as claimed in claim 1 in which the means adapted to concentrate the light passing to the light sensitive surface comprise optical means acting to form a single spot of light thereon of constant shape.

10. Apparatus for use in telephotography as claimed in claim 8, in which said optical means comprise lenses adapted to bring to a point on said light sensitive film rays travelling from said light source to said light sensitive surface in planes substantially at right angles to one another.

In testimony whereof we have signed our names to this specification.

HARRY GUY BARTHOLOMEW.
MAYNARD L. D. McFARLANE.
